UNITED STATES PATENT OFFICE

JOHN SNEED, OF GROSSE POINTE SHORES, MICHIGAN

METHOD OF FORMING LINKS

Original application filed July 16, 1928, Serial No. 293,107. Divided and this application filed November 25, 1929. Serial No. 409,540.

This invention relates to links or tie rods and more particularly to a method of making them. This application is a division of my copending United States application Serial 5 No. 293,107, filed July 16th, 1928.

It is among the objects of my invention to form a link essentially of one piece of sheet stock; to provide a link and method of making same having the attributes of strength, 10 durability, economy and neatness of appearance; to provide a method of forming the type of link disclosed in the above mentioned copending patent application by a simple and economical process.

15 Other objects will appear from the following description of a preferred form of my invention in which the article and the steps of a preferred method are described in detail. The precepts of my invention are equally applicable to such devices as drag links in the steering mechanism and connecting links in shock absorbers etc. The essential characteristics are summarized in the claims.

In the drawings, Fig. 1 illustrates the embodiment of my link as a tie rod between the steering arms of the swiveling wheels of a motor vehicle; Fig. 2 is a partially broken longitudinal section of the link and the assembled parts at the end; Fig. 3 is a view 20 taken on the line 3—3 of Fig. 2 illustrating the end contour of my link; Fig. 4 is a bottom plan view of one end of the link; Fig. 5 illustrates the blank of sheet stock from which the link may be formed; Fig. 6 is a 25 partial longitudinal section of the female die used in the first step of the forming operation of the link; Fig. 7 is a partial side elevation of one end of the link after the first forming step; Fig. 8 is a top plan view of 30 the piece in the same stage; Fig. 9 is a section taken on the line 9—9 of Fig. 7; Fig. 10 is a section taken through the end of the female die used in the second forming step; Fig. 11 is a section illustrating the relation 45 of the link and the several dies at the end of the second step showing an ejecting and centering die or mandrel.

50 Referring to Fig. 1, I show the link or tie rod L joining steering arms 1 and 2. As is the usual practice the steering arms are car-

ried by swiveling stub axles which pivot about inclined axes. As the wheels swivel the end of the one of the steering arms falls while the end of the other steering arm rises so that universal connections are desirable between 55 the ends of the link and the steering arms. In the embodiment of my link as a tie rod for the front wheels of a motor vehicle, it is also desirable that the ends of the steering arms be moved toward or away from each other to 60 align the wheels.

Referring to Figs. 2 and 3, the link member L comprises a longitudinally extending cylindrical portion 10 with integrally formed cupped ends 11 and 12. As illustrated in 65 Fig. 2, the upper parts of the cupped ends 11 and 12 are hemispherically formed and merge into depending cylindrical parts of like radius. Generally speaking the end portions 11 and 12 comprise sockets for holding and permitting universal movement of connecting and adjusting members 13 and 14. The axes of the cylindrical parts of the cupped ends preferably extend at right angles to the longitudinal axis of the link. The intersections of the axes determine the centers of the hemispherical parts of the cups. Each of the cupped ends have a central aperture 11e and 12e punched in the hemispherical part 70 through which the shank of one of the members 13 and 14 extends.

The connecting members 13 and 14 may be similar. The member 13 comprises a substantially spherical ball portion shown at 15 which is held in a socket in the end portion of 85 the link. Opposite the ball end is a tapered shank 17 the axis of which is offset from the center of the ball. The ends of the steering arms 3 and 4 have conically formed seats into which the tapered shanks of the members 13 and 14 are secured by nuts 5 and 6 threaded on extensions of the members. The ends of the threaded extensions may be slotted as at 90 7 and 8 to be held against rotation. I prefer that the ball parts of the connecting members 95 13 and 14 be carried by the link, but if it be desired, the ball parts may be carried by the steering arms or its equivalent and the tapered shank may be carried by the link. The principal of this phase of my invention 100

being that the offset shanks facilitate adjustment while the ball parts permit universal movement between the link and the members between which it serves.

- 5 To move the ends of the steering arms 3 and 4 toward or away from each other, one or both of the shanks of the members 13 and 14 may be turned with relation to the ends of the steering arms and the arms will be moved by 10 reason of the eccentricity of the axes of the shanks with relation to the centers of the balls. Thus if the offsets be an eighth of an inch per member, a gross over-all adjustment of one-half inch may be obtained between the 15 ends of the steering arms.

In the preferred form of my invention I desire to support the ball parts of the connecting members in an assembled socket between which is incorporated a lubricating device 20 and chamber. In Fig. 1 there is illustrated a tubular bushing or bearing member 20 which has a concave spherical surface 21 forming the upper part of the socket. The member 20 extends through the cylindrical 25 part of the end portion of the link with shoulders resting against the periphery of the aperture 11e. The upper edge of the member is peened over as at 22 and is thereby permanently secured in the end of the link. The 30 cylindrical walls of the cupped end closely fit and support the member. When the member 20 is secured in the end of the link, the lower longitudinal seam 40, see Fig. 4, and the joint 41 in the cylindrical part of the cupped 35 end are welded, as at 42, see also Figs. 2 and 3.

After the members 20 are secured in the cupped ends, the ball stud connecting members 13 and 14 are inserted so that the ball portions rest upon the surfaces 21. Then a 40 member 25 is inserted in the member 20 to engage the ball portion along the surface 27 to complete the socket, see Fig. 2. A short coil spring 26 is compressed between the member 25 and a closure member 28. The closure 45 member 28 may be permanently secured by inturning the lower edge of the member 20 as at 29. Lubricant fittings 30 of any well known type may be threaded into the member 29 so that lubricant may be forced into the chamber defined by the member 20. The member 25 has a central aperture in its bearing surface both for the admission of lubricant and for the admission of such means as 50 a drift pin for driving the shank of the ball stud into the conical seat in the end of the steering arms.

Referring particularly to Figs. 5 to 11, I 55 will describe a preferred method of forming the link. The blank from which the link may be formed is illustrated in Fig. 5 and comprises a longitudinally extending rectangular part 10a with substantially disc-like ends 11a and 12a. The junction between the 60 disc-like ends and the middle rectangular

portion may be cut as at 41a to provide an excess of metal to close the joint at 41, see Fig. 4.

Referring to Figs. 6 to 9 inclusive, the blank is forced into a female die 60, partially illustrated in Fig. 6, which comprises primarily a longitudinally extending channel part 61, the bottom of which is semi-cylindrical so that the mid portion 10 of the link is drawn to a semi-cylindrical section 10b, see Fig. 9. The die 60 has at both ends a substantially hemispherical bottom 62 struck from a sphere whose center C lies coincident with the axis of the semi-cylindrical part 61 of the die. The whole die may have an adjustable insert not shown so that the distance between centers C determines the distance between which the center of the balls 15 will be spaced apart in the finished link. The parts of the die 60 directly above the hemispherical part 62 are substantially cylindrical as at 63. The piece is drawn by a complementary male die not shown and is thus formed with cupped ends partially spherical in form as at 12b and partially cylindrical 60 in form as at 12c.

Referring to Figs. 10 and 11 the piece having been formed to the shape shown in Figs. 7 to 9 is inverted with its open edge facing the die 70 and with the cupped end portions carried by retractable dies or mandrels 80. The dies 80 may be resiliently or otherwise retractably supported and serve to space the end portions and hold the walls thereof during the last forming operation. A downwardly moving die 71 having a contour similar to the die 60 urges the piece downwardly into the die 70. In this operation the edges of the channel 10c, see Fig. 9, are moved toward each other along the surface 72 of the die 70 into a cylindrical form illustrated at 10 in Figs. 2 and 3. During the same motion of the die, the parts 41a, see Figs. 5, 7, 9 and 11 are moved and drawn toward each other until they meet as at 41, see Fig. 4. There remains the operation which is not shown of punching out openings 11e and 12e in the spherical domed part of the end portions. As mentioned above and as shown in Figs. 2, 3 and 4, the joints 40 and 41 are welded as at 42 both for the purpose of filling the joint and of securing the edges together adjacent the ends of the link.

Although my improved method of forming links has been described and illustrated as applied to the manufacture of tie rods for connecting the swiveling wheels of a motor vehicle, I do not care to be limited in its application particularly to a tie rod. While I have described a method of forming one form of tie rod, I do not care to be limited by the particular description or in any manner other than by the claims appended hereto.

I claim:

1. The method of making a tie rod for use in vehicle steering gear with integral cupped ends from sheet stock which consists in drawing the stock into a longitudinally extending channel part and into partially spherical and partially cylindrical end parts, bringing the edges of the channel part together along a longitudinal seam to form a tubular part and forcing the stock adjacent the ends of the seam in the cylindrical portion of the end parts together to form a closed cylinder while holding the end parts against movement toward each other. 70
2. The method of making a tie rod for use in vehicle steering gear which consists in forming a unit with cupped ends, punching openings in the bottom of the cupped ends, placing tubular members in said ends with their walls engaging the walls of the cups and with the ends of the tubular members extending through said openings and thereafter peening the ends of the tubular members over the peripheries of said openings 5 to secure the tubular members in the cupped ends. 80
3. The method of making a tie rod from sheet stock which consists in drawing a channeled mid-portion with cupped ends disposed normal to the channel portion, holding the ends against movement toward or away from each other and forcing the edges of the channel together to form a tubular part with a longitudinal seam and drawing together the 15 walls of the cupped ends adjacent the seam to form the closed cylindrical part of the cup with a joint adjacent the seam, pressing into the cupped ends a bushing or bearing part and thereafter welding together at least the 20 ends of the seam and the said joint. 85
4. The method of forming a tie rod for use in vehicle steering gear from sheet stock which consists in drawing a blank into a channel shaped mid-portion with cup shaped 45 end portions, forcing the edges of the channel together to form a tubular body for the link, and closing the brims of the cupped ends and welding at least the ends of the seam in the tubular body and the joints in 50 the brims of the cupped parts. 90
5. The method of forming a tie rod for use in vehicle steering gear which consists in drawing from sheet stock a channel part with cupped ends, the cupped ends being drawn to greater depth than the channel, then holding the cupped ends against movement toward or away from each other while forcing the edges of the channel section toward each other to form a tubular middle part for the 55 link. 95
6. The method of making a tie rod for use in vehicle steering gear with integral cupped ends from sheet stock which consists in drawing the stock into a longitudinally extending 60 channel part and into partially spherical and
- partially cylindrical end parts, bringing the edges of the channel part together along a longitudinal seam to form a tubular part and forcing the stock adjacent the ends of the seal in the cylindrical portion of the end parts to form a closed cylinder while holding the end parts against movement toward each other. 75
7. The method according to claim 6 which includes punching openings in the cupped ends, inserting sleeves through the openings and peening the ends of the sleeves over the periphery of said openings. 80
8. The method of forming a tie rod which consists in pressing from sheet stock a body part and drawing cupped ends from the same stock each with a substantially hemispherical portion and an integral incomplete cylindrical portion of like radius and thereafter holding the said substantially hemispherical portions a fixed distance from each other while drawing the walls of the cylindrical portions together to form complete cylindrical portions. 85
9. The method of forming a tie rod for use in vehicle steering gear which consists of stamping a sheet metal blank into a longitudinally extending portion of U-shaped cross section with cup shaped end portions having cylindrical side walls and spherically formed base portions, closing the open U-shaped longitudinal portion to form a tubular portion and completely closing the top edge of the cylindrical walls of said cup shaped portion. 90
10. The method of forming a link which consists in drawing from sheet stock a channel part with cupped ends, the cupped ends being drawn to greater depth than the channel and thereafter apertured, and forcing the edges of the channel part toward each other to form a tubular middle part for the link. 105
11. The method of making a link which consists in drawing from sheet stock a channel part with cupped ends, the cupped ends being drawn to greater depth than the channel, forcing the edges of the channel part toward each other to form a tubular middle part for the link, punching openings in the cupped ends, inserting sleeves through said openings and peening the ends of said sleeves over the edges of said openings. 110
12. The method of making a link from sheet stock which consists in drawing a channeled mid-portion with cupped ends, forcing together the edges of the channel to form a tubular part with a longitudinal seam, punching openings in the cupped ends, inserting sleeves through said openings, peening the ends of said sleeves over the edges of said openings and welding together at least the end portions of said longitudinal seam. 120
13. The method of making a tie rod from sheet stock which consists in drawing a channeled body portion with cup shaped ends 130

having an open side, holding the ends against movement toward or away from each other and forcing the edges of the channeled body portion together to form a tubular part with 5 a longitudinal seam and thereafter pressing a bushing or bearing into said cupped end portions.

14. The method of making a link with integral cupped ends from sheet stock which 10 includes punching openings in the cupped ends inserting sleeves through the openings and peening the ends of the sleeves over the periphery of said openings.

15. In testimony whereof I hereunto affix my signature this 22nd day of November, 1929.
JOHN SNEED.
